UNITED STATES PATENT OFFICE.

JOHN PELLETIER AND MICHAEL PELLETIER, OF NEW YORK, N. Y.

DESIGN FOR A PICTURE FRAME.

Application filed December 12, 1927. Serial No 24,454. Term of patent 14 years.

To all whom it may concern:

Be it known that we, JOHN PELLETIER and MICHAEL PELLETIER, citizens of the United States, residing at 828 East 227th St., New York, in the county of Bronx and the State of New York, have invented a new, original, and ornamental Design for a Picture Frame, of which the following is a specification, reference being had to the accompanying drawing, forming part thereof.

Figure 1 is a plan view of a picture frame, showing our new design.

Figure No. 2 is a side or edge view of the picture frame to show its appearance when viewed from the side.

We claim:

The ornamental design for a picture frame, as shown:

JOHN PELLETIER.
MICHAEL PELLETIER.
